UNITED STATES PATENT OFFICE.

CHARLES LA DOW, OF ALBANY, NEW YORK.

ART OR METHOD OF GOVERNING THE FLIGHT OF MULTIMISSILE PROJECTILES.

SPECIFICATION forming part of Letters Patent No. 776,918, dated December 6, 1904.

Original application filed January 7, 1904, Serial No. 187,998. Divided and this application filed August 8, 1904. Serial No. 219,970.
(No model.)*To all whom it may concern:*

Be it known that I, CHARLES LA Dow, a citizen of the United States, residing at Albany, in the county of Albany and State of New York,

- 5 have invented certain new and useful Improvements in the Art of Effecting Close Shooting of Projectile Charges Made Up of a Number of Separate Missiles, of which the following is a specification.
- 10 This invention consists in the method or art of holding together and causing to be thrown as a relatively solid or compact mass a projectile charge made up of numerous separate and distinct missiles.
- 15 The present application is a division of one filed in my name on the 7th day of January, 1904, and designated by Serial No. 187,998, wherein is claimed generically the art or method as applied to the control of the flight 20 of multimissile projectiles, the present application being intended to cover specifically and alone such method as applied to the concentration or holding together of the portions of the projectile charge. This matter is placed 25 in a separate application and patent for the reason that under the rules and practice of the Patent Office while a generic claim and a claim to one specific form or embodiment of the invention are permissible in one application and patent it is not permitted to claim 30 therein two specifically-different embodiments of the invention, and it is my purpose to make specific claim through the parent application and the present case both to the art or method 35 of effecting a spreading or diffusion of the missiles and to the art or method of concentrating or holding together the missiles of a multimissile charge.

For certain classes of shooting it is desirable 40 that the shot or other missiles constituting the projectile charge be caused to travel in a relatively compact mass, so that at a predetermined distance they shall cover a comparatively small area on the target or other 45 object aimed at. This may be desirable for either of two reasons—first, in order to utilize against large game a charge which if allowed to scatter to any considerable extent would be ineffectual to kill or seriously cripple a large

animal, and, second, in order that the charge 50 may be thrown to and made effective at greater distances than it would be if permitted to separate sooner.

I have discovered that if the gases incident to the burning or explosion of the propelling 55 or powder charge be allowed to pass to or into the projectile charge at or close to its circumference just before or at the time the projectile charge leaves the gun the missiles making up said charge will, by reason of the pressure inward as well as outward of the enveloping gases, be held together and caused to maintain a relatively compact formation for a considerable distance after leaving the muzzle of the gun. This direction of the 60 gases to the circumference or periphery of the projectile charge may be effected in a variety of ways; but in view of existing conditions and of the greater convenience of fixed ammunition it is preferred ordinarily to use 65 such fixed ammunition, and I have for this reason illustrated my invention as embodied therein, but it is to be understood that I do not restrict myself thereto.

Referring to the accompanying drawings, 75 Figure 1 is a longitudinal central section of a cartridge loaded in a manner to produce concentration or holding together of the missiles making up the projectile charge. Figs. 2, 3, 4, 5, and 6 are views illustrating some of the 80 many forms of wads suitable for use between the propelling and projectile charges to effect the purposes of the present invention, these wads being represented as contained within a shell to better illustrate the construction and 85 principle of operation; and Fig. 7 is a perspective view of the composite wad shown in Fig. 1.

In the drawings, A indicates a shell, which may be of any usual form or construction, 90 but which is here represented as having a paper or pasteboard body with a reinforced base of paper in convolute form and a metallic flanged head, as is common in shot-cartridges.

B denotes the propelling charge of powder.

C and D indicate wads interposed between the powder charge B and the projectile charge

E, which latter is here represented as composed of a number of loose shot.

F indicates a retaining-wad placed outside or in front of the shot and held in the shell by turning or crimping the forward or front end of the shell in a manner usual and well understood. The matter of crimping is optional, since any usual way of holding the retaining-wad in position may be resorted to, the same being no part of the present invention.

In Fig. 1 the wads C and D, interposed between the propelling and projectile charges, together make up a separating body or medium suitable to the carrying out of the purposes of the present invention, though other forms and combinations of wads or separating mediums may be used. In other words, it is to be understood that the illustrations here given are merely suggestive of possible types. With the specific arrangement illustrated in Fig. 1 the powder upon being ignited by the primer G develops or generates gases which pass through the central opening a of wad C and find their way in limited degree between the proximate faces of wads C and D and through the peripheral notches or passages b to the circumference of the projectile charge E. The pressure of the gases upon wad C causes said wad to be held so closely to wad D that only a relatively small portion of the gases can thus pass to the projectile charge as the latter moves through the barrel of the gun; but as the forward wad D is relieved of the circumferential friction in advance of wad C a greater separation is believed to occur at the instant that wad D emerges from the gun, and as a consequence the gases are permitted to pass in greater quantity between the wads and through the notches or passages b and to move forward around the projectile charge E, thereby effectually and completely enveloping said charge and serving to hold the same in a compact mass. By arranging the two wads so that each practically closes the openings or passages of the other while the charge is passing through the gun undue or injurious escape of gases to a point in advance of the wads is precluded.

The foregoing is believed to be a correct statement of what actually takes place within the gun, though from the nature of the case it is impossible to say with absolute certainty that this is the correct theory or an exact statement of the action occurring. Whatever may be the fact as to this, it has been definitely ascertained that a shell constructed or loaded in the manner stated does cause the projectile charge to move in a more compact mass than when loaded in the ordinary way or with wads of customary form.

Fig. 2 represents a wad D of the form shown in Fig. 1. This and other forms, about to be referred to, are represented as contained within a shell A.

Fig. 3 shows a wad D', having its periphery clipped or cut away at four points, leaving segmental bearing portions c to fit the bore of the shell and of the gun and maintain the wad in its proper relation to other portions of the charge and to the bore of the gun.

Fig. 4 shows a wad D'', having recesses similar to those in the wad illustrated in Fig. 2, but of larger size and fewer in number. In both cases, and, in fact, in all cases, it is desirable that the openings or passages, however produced, be symmetrically arranged or even distributed about the center or axis of the wad and charge.

In Fig. 5 there is shown a wad D''' similar to that illustrated in Fig. 3, except that the segmental bearing-faces c of Fig. 3 are removed, leaving only contact-points instead of extended surfaces.

In Fig. 6 a wad D⁴, having a series of perforations near, but not actually opening to, the circumference is shown.

Fig. 7 is a perspective view of the wad shown in section in Fig. 1, wad C having the central perforation a and wad D the peripheral notches b, before referred to.

While I have illustrated and described the invention as applied to a shot-cartridge, it is to be understood that it comprehends large charges and projectiles—such, for instance, as canister, shrapnel, and the like—the principle remaining unchanged and the difference being merely one of size or degree.

No claim is made herein generically to the mode of controlling the flight of a multi-missile charge, since such generic claim is made in application Serial No. 187,998, of which, as before stated, this is a division; but a claim is specifically made herein to the direction of the gases to the circumference of the charge and the enveloping of the charge by such gases for the purpose of effecting concentration or holding together of the charge and consequent "close shooting." The means by which this is effected will not be claimed herein, being made the subject-matter of separate application filed in my name on the 8th day of August, 1904, and designated by Serial No. 219,972.

Having thus described my invention, what I claim is—

1. The herein-described art or method of effecting and controlling a concentration or holding together of the separate missiles constituting a projectile charge, which consists in delivering and directing to the projectile charge at or near its circumference a portion of the gases incident to the burning or explosion of the propelling charge, and preventing the entrance thereof into said charge at its axis.

2. The herein-described art or method of effecting "close shooting" or holding together of the missiles constituting a projectile charge, which consists in causing the gases incident

to the burning or explosion of the propelling charge to enter the projectile charge at or close to its circumference and to envelop said charge as the latter leaves the muzzle of the gun, whereby the missiles are prevented from freely separating and spreading apart.

5 In testimony whereof I have signed my name

to this specification in the presence of two subscribing witnesses.

CHARLES LA DOW.
